UNITED STATES PATENT OFFICE.

EDWARD T. FENWICK, OF WASHINGTON, DISTRICT OF COLUMBIA.

DESIGN FOR A SPOON OR SIMILAR ARTICLE.

SPECIFICATION forming part of Design No. 21,565, dated May 24, 1892.

Application filed April 29, 1892. Serial No. 431,221. Term of patent 3½ years.

To all whom it may concern:

Be it known that I, EDWARD T. FENWICK, a citizen of the United States, residing at Washington, in the District of Columbia, have 5 invented and produced a new and original Design for Spoons or other Similar Articles; and I do hereby declare the following to be a full, clear, and exact description of the same, reference being had to the accompanying 10 drawing, forming a part thereof.

This design is intended to be symbolic of the "Christian Endeavor Society."

The drawing represents a spoon having upon it the representation of a church and the representation of a person holding a light.

The leading features of my design are the representation of a church—such as the "Wil-

liston Church," situated at Portland, Maine—and a representation of a person holding a light, which may be emblematic of Christ, 20 the Light of the World.

With the above features a monogram or logotype and suitable mottoes, words, and scrolls may be employed; but these form no essential part of this design. 25

What I claim is—

The design for a spoon or similar article, substantially as shown and described.

In testimony whereof I hereunto affix my signature in presence of two witnesses.

EDWARD T. FENWICK.
